UNITED STATES PATENT OFFICE

HARLAN W. HOW, OF BUFFALO, NEW YORK, ASSIGNOR TO BUFFALO FOUNDRY & MACHINE COMPANY, OF BUFFALO, NEW YORK, A CORPORATION OF NEW YORK

EVAPORATOR

Application filed January 12, 1927. Serial No. 160,748.

This invention relates to an evaporator of the type which is provided with a plurality of small up-take tubes arranged in a heating chamber and adapted to carry the liquor upwardly from a lower return chamber to an upper vapor chamber, and a large downtake tube arranged within the heating chamber and communicating at its upper and lower ends with said vapor and return chambers, respectively.

Heretofore it has been customary to employ an ordinary marine propeller either in the downtake tube or immediately below the same to assist in circulating the liquor, but this organization is very inefficient and wasteful of power.

The object of this invention is to provide an impeller which virtually creates a static head underneath the tube sheet at the lower ends of the small up-take tubes instead of depending on velocity to create the necessary upward circulation, thereby increasing the efficiency and saving power, and obtaining a more rapid circulation and a corresponding increase in the capacity of the heating surface.

In the accompanying drawings:

Figure 1 is a vertical section of an evaporator embodying an approved form of my invention. Figure 2 is a fragmentary vertical section of a modified form of part of the improvement. Figure 3 is a horizontal section, on an enlarged scale, taken on line 3—3 Fig. 1. Figure 4 is a plan view, on an enlarged scale, of the impeller.

Similar characters of reference indicate like parts in the several figures of the drawings.

The numeral 10 represents a heating chamber which is adapted to receive steam or other heating agent from any suitable source through an inlet 11 in its side wall 12 and discharge the water of condensation through a pipe 13 and any trapped air through a vent pipe 14.

Above the heating chamber is arranged a vapor chamber 9 in which the vapors from the liquor are drawn off by any suitable means through a vapor outlet 15 in the top 16 of the vapor chamber. The side wall 17

of the vapor chamber is provided with the usual windows 18 to permit of observing the condition of the liquor as evaporation progresses. Below the heating chamber is arranged the return chamber 19 which is provided in its bottom with a manhole through which access may be had to the interior of the return chamber, which manhole is normally closed by a cover 20.

A plurality of small upright up-take tubes 21 are arranged in an annular group within the heating chamber adjacent to the outer wall thereof, which tubes have their upper ends communicating with the vapor chamber and secured in an upper flue sheet 8 separating the heating and vapor chambers while the lower ends open into the return chamber and are secured in the lower flue sheet 22 which separates the heating and return chambers.

Arranged centrally within the heating chamber is a large down-take tube 23 which has its upper and lower end communicating with the vapor and return chambers and secured in the upper and lower flue sheets.

My improved means for producing a more rapid circulation of the liquor through the tubes, vapor chamber and return chamber are constructed as follows:

Extending downwardly from the lower end of the large central down-take tube is an impeller casing, the central part 7 of which is contracted to a diameter somewhat smaller than the bore of the downtake tube while its upper part 24 flares upwardly to a diameter corresponding to the bore of the downtake tube and the lower part 25 of the casing flares downwardly on a curve in the form of a trumpet. This casing may be either formed separately from the downtake tube and secured to the lower end thereof, as shown in Fig. 1, or the same may be formed integrally with the downtake tube, as shown in Fig. 2.

Within the lower part of the impeller casing is a rotary impeller which comprises an upwardly coned body 26 which is separated by an intervening space from the lower end of the casing, and a plurality of impeller blades 27 of spiral form arranged in an annular row on the upper side of the impeller body

and each blade having its upper edge arranged close to the inner side of the lower part of the impeller casing and curved so as to conform to the contour of this part of the casing.

5 This impeller rotates about a vertical axis which is coincident with the axis of the downtake tube and is driven by power from the exterior of the evaporator.

10 In its preferred form this driving mechanism consists of an upright shaft 28 journaled in a bearing 29 and packed in a stuffing box 30 on the bottom of the return chamber, the upper end of this shaft being secured to the center of the impeller body, and the lower end of the same being connected with a driving mechanism 31 of any approved character arranged outside of the evaporator and receiving its power from any suitable source.

15 Upon turning the body and blades of the impeller a powerful downward suction is produced in the downtake tube which causes the liquor to be drawn downwardly, discharged laterally through the entire peripheral space between the impeller body and the flared lower end of the casing, and pressed from the return chamber upwardly through the small up-take tubes into the 20 vapor chamber. The liquor is by this means circulated very rapidly and with a saving of about one-half the power heretofore required to do a given amount of work, thereby not only increasing the output of the 25 evaporator but also effecting a material reduction in the cost of evaporating the liquor.

30 I claim as my invention:

35 A circulator for evaporators of the character described, comprising an upright conduit having an upper section having a cylindrical wall of comparatively large diameter, an intermediate section having a tapering wall which reduces downwardly from the lower end of said cylindrical wall and a lower section having a flaring wall which enlarges downwardly from the lower small end of the wall of said intermediate section and extends with its lower edge laterally beyond the wall of the upper section; and a 40 rotary impeller having a conical body arranged below said conduit and axially in line therewith and having its point projecting upwardly into the lower and intermediate sections of said conduit and having its wall flaring downwardly from said point at a distance from the wall of said lower conduit section and forming between the latter and the body of said impeller an annular outlet 45 passage which in radial section is wide at the top and gradually reduces downwardly toward the narrow lower end thereof; and blades arranged on the upper side of said impeller body and in the downwardly reducing space between the marginal part

thereof and the inner side of the wall of said lower conduit section.

50 In testimony whereof I hereby affix my signature.

HARLAN W. HOW.
